(57) **CLAIM**

The ornamental design for a portable desktop instrument for the assessment of behavioral and neurological disorders, as shown and described.

DESCRIPTION

FIG. 1 is a perspective view of a portable desktop instrument for the assessment of behavioral and neurological disorders deployed in a first position.

FIG. 2 is a front elevational view thereof.

FIG. 3 is a left elevational view thereof.

FIG. 4 is a back elevational view thereof.

FIG. 5 is a right elevational view thereof.

FIG. 6 is a top plan view thereof.

FIG. 7 is a bottom plan view thereof.

FIG. 8 is a top plan view of a portable desktop instrument for the assessment of behavioral and neurological disorders deployed in a second position.

FIG. 9 is a front elevational view thereof.

FIG. 10 is a right elevational view thereof.

FIG. 11 is a left elevational view thereof.

FIG. 12 is a bottom plan view thereof; and,

FIG. 13 is a perspective view thereof.

The broken-line disclosure in the figures illustrates examples of an intended environment for illustrative purposes only and forms no part of the claimed design.
